UNITED STATES PATENT OFFICE.

HERBERT CLINTON KELLOGG, OF MINNEAPOLIS, MINNESOTA, ASSIGNOR OF ONE-HALF
TO CHARLES A. RICKERT, OF MINNEAPOLIS, MINNESOTA.

RAZOR-BLADE SHARPENER.

Application filed May 26, 1924. Serial No. 715,786.

My invention relates to improvements in razor blade sharpeners.

An object of the invention is to provide a power driven sharpener of the present nature designed to accommodate a plurality of blades, yet consisting of a limited number of parts capable of production at relatively small cost and capable of long use without incapacitating wear.

10 Another object of the invention is to provide a device of this kind, wherein the interchanging of blades may be readily accomplished without discontinuing the operation of the machine.

15 A further object is to supply a sharpener of the present nature employing finishing and honing surfaces as well, the blade holders being adapted to be stationed with respect to said surfaces, whereby the desired 20 abrasive action of said surfaces is had with the blades in their holders.

With the foregoing and other objects in view, which will appear in the following description, the invention resides in the novel 25 combination and arrangement of parts and in the details of construction hereinafter described and claimed.

In the drawings, Fig. 1 is a plan view of 30 a sharpener embodying my invention; Fig. 2 is an elevational view thereof; Fig. 3 is a vertical sectional view taken on the line 3—3 of Fig. 1; Fig. 4 is a perspective view, in detail, the same illustrating one of the 35 holder bar mountings; Fig. 5 is a sectional view taken transversely of said mounting as on the line 5—5 of Fig. 1; Fig. 6 is an enlarged sectional view of the forward end 40 of a blade holder bar, the same being taken as on the line 6—6 of Fig. 3 and Fig. 7 is an enlarged sectional view, in detail, taken as on the line 7—7 of Fig. 2.

Referring to the drawings, it will be observed that my improved sharpener includes a frame A comprising a bed 10 formed with 45 legs 11 thereon and brackets 12, 12^a rising from the ends of the bed 10. Journalized at its ends in said brackets 12, 12^a is a shaft 13 upon which spaced discs 14, 14^a are axially fixed. These discs are arranged in pairs, the 50 discs 14 being provided, with leather facings 14' and the discs 14^a with facings 14'' of stone or other suitable honing material. The break through the device indicates that the use of additional discs 14 is contem-

plated, six pairs of these discs being most 55 practical, since that number provides for the simultaneous sharpening of blades in dozen lots. Paralleling the shaft 13 are two supporting bars 15, 15^a, which extend from the bracket 12 to the bracket 12^a along opposite sides of the disc assembly, said bars being supported at intervals between said brackets 12, 12^a by means of standards 10^a 60 rising from the bed 10. The reach of said supporting bar 15 alongside the discs 14 65 rests at an elevation above the shaft 13, that portion of said supporting bar 15 at the side of the discs 14^a being depressed and lying at a lower elevation than that of said shaft 13. The location of the corresponding 70 reaches of the supporting bar 15^a is reversed with respect to the reaches of the bar 15, above described, as will be seen in Fig. 2 of the drawings.

For each pair of discs 14, 14^a, I provide 75 two blade holder mountings B, one of which is carried by the supporting bar 15 and the other by the supporting bar 15^a. These mountings are identical, each including an elongated body 16, the same being pivoted 80 between the ends thereof, as by means of a pin 17 to its respective supporting bar 15 or 15^a. The inner extremity of each body 16 reaches inward between the facing, abrasive surfaces of its respective pair of discs 85 14 or 14^a, the outer extremity of the body 16 having affixed thereto a U-shaped member 18, as shown (Fig. 5). A yoke-like receiver 19 having outwardly flared, yielding branches 19^a is swiveled on the forward end 90 of each body 16 and a similar receiver 20 is interposed between the flanges 18^a of the member 18 at the opposite end of the body 16. Said flanges 18^a have opposed set screws 95 21 (Fig. 5) threaded therein to variously hold their respective receivers 20 laterally of their respective bodies 16.

A blade holder C is provided for each 100 mounting B, each holder comprising a shank 22 with opposed, yielding jaws 23 thereon adapted to receive a razor blade. The jaws 23 of each holder C are brought into gripping engagement with a blade inserted between them through the medium of a bolt 24 and nut 25 (Fig. 6), said bolt being 105 extended through said jaws and formed with a head 24^a designed to cooperate with one of the jaws and prevent the turning of

the bolt with respect to said jar. Finger-pieces 25^a on the nuts 25 provide for ready manipulation thereof, whereby the application to and removal of blades from the 5 holders C is quickly and easily accomplished.

The holders C are interchangeable in the holder mountings B, the shank 22 of any holder being adapted to snugly fit in the receivers 19, 20 of any holder mounting B. A gauge-pin 26 reaching through the shank 22 of each holder is designed to abut against the rearward edges of the branches 19^a of its respective receiver 19. These pins guide 15 the operator in applying the holders C to the mountings B and prevent said holders from being drawn forward and out of operative positions in their mountings by the action of the discs 14, 14^a on the blades 20 held in said holders.

The shaft 13 is driven in one direction (counter clock-wise, Fig. 3) by means of a belt 27 passing over a pulley 28 on said shaft and a pulley 29 on the shaft 30 of a 25 motor 31 secured to the underside of the bed 10.

Mechanism is supplied for rocking the holders B to and fro between their respective discs 14 or 14^a. Shifter bars 32, 32^a extending along opposite sides of the disc assembly are pivoted, as by means of pins 33, to the bodies 16 of the mountings B on their respective sides of said assembly. A tie-bar 34 joins the shifter bars 32, 32^a, the former 30 being pivoted to one end of said tie-bar, as at 35, and the latter having a slideable pivotal connection with the other end of the tie-bar 34, as at 36, journaled on a spindle 37 rising from an arm 38 on the bracket 12 is a worm 40 wheel 39, the same meshing with a worm gear 40 on the shaft 13. An elongated protuberance 39^a rising from the upper face of the worm wheel 39 and extending diametrically thereof has a way 39^b formed therein. A block 41, slideable in this way 39^b is adjustably held in various positions radially of the worm wheel 39 by means of opposed set screws 42 threaded longitudinally in said protuberance 39^a. A pitman rod 43, 45 having an angular extremity 43^a threaded downwardly in said block 41, reaches in approximate parallelism with the shaft 13 to the tie-bar 34 to which it is pivotally connected, as at 44. Rotation of the shaft 13 by the motor 31, causes the rotation of the worm wheel 39, which functions as a crank wheel, the motion of said worm wheel being transmitted through the pitman rod 43, tie-bar 34 and shifter bars 32, 32^a to the 50 holder mountings B. With blades fitted in the holders C and said holders applied to the mountings B, said blades are rocked back and forth between the abrasive surfaces of their respective discs 14 or 14^a. To increase or diminish the pressure of said

blades against the sharpening surfaces of the discs, it is only necessary to suitably shift the block 41 in the way 39^b. If, through inherent or attained structural inaccuracies in a holder C or mounting B, 70 the blade therein is caused to bear against one of the abrasive surfaces of its respective discs with greater pressure than it does against the opposing abrasive surface, this may be corrected and such pressure equalized 75 by suitably adjusting the set screws 21 in the member 18 of the mounting B. In this connection and remembering that the forward receiver 19 is swiveled on the body 16, it will be understood that the adjustment of 80 the receiver 20 from one side to the other will result in variously stationing the forward end of a holder C between its respective discs, whereby the pressure of a blade 85 against the abrasive facings on said discs may be readily attained.

In use, the resharpening of blades does not ordinarily require the honing thereof, in which event the discs 14 faced with leather or other finishing surfaces are employed. 90 Confining himself to the use of said discs 14 and having attained the proper adjustment of the block 41 in the way 39^b and of the receivers 20 on the bodies 16, the operator has only to change the blades in the holders C 95 as they become sharpened, it being necessary, of course, to reverse the blades of the double edged type. In changing a blade, the operator lifts the holder C from its mounting B as it carries the blade away from one of its 100 sharpening discs. Detached from its mounting, the holder C is easily manipulated to free a blade and to take a new grip on said blade, when reversed, or to take a grip on a fresh blade. Again fitted with a blade, the holder C is readily seated in the receivers 19, 20 of its mounting B as said mounting swings away from one of the discs toward 105 its companion disc. The arrangement of the mountings B for the discs 14, provides 110 for a movement of the abrasive surfaces away from the edges of the blades as will be observed in Fig. 3. This provision is desirable in finishing the cutting edges of blades, but is not entirely practical in honing. 115 To provide for movement of abrasive surfaces against the edges of the blades, I have arranged the mountings B for the discs 14^a in a manner, which is the reverse of that of the mountings B for the discs 14. This variation in the arrangement of the mountings B with respect to the discs 14, 14^a is best 120 seen in Figs. 2 and 3. In these figures, it will be observed that the sharpening surfaces of the discs 14^a turn against the edges of the blades presented thereto, which surfaces of stone or other suitable material effectively hone said blades. The use of the discs 14^a does not interfere in any way with 125 the use of the discs 14. Blades applied to 130

said discs 14^a in identically the same manner as they are to the discs 14, are readily honed, when that is necessary, while the finishing of other blades is being effected by the discs 14.

Among the numerous advantageous features resident in my present improvement, attention is particularly invited to the compactness of the device, its relatively few parts, the large capacity thereof and the ability of the improvement to meet the different needs as noted above.

Changes in the specific form of my invention, as herein disclosed, may be made within the scope of what is claimed without departing from the spirit of my invention.

Having described my invention, what I claim as new and desire to protect by Letters Patent is:

1. In a device of the class described, a frame, a pair of spaced discs, one facing the other and each provided with an abrasive facing, means for turning said discs, a support, a mounting, including an elongated body pivoted on said support, yoke-like receivers spaced longitudinally of said body, one receiver being swiveled on the body and the other movable laterally thereof, and means for securing said laterally movable receiver in adjusted positions, a blade holder for the mounting, comprising a shank and blade gripping jaws on the shank, said shank being removably applicable to said receivers, and means for swinging said body to oscillate the holder and thereby carry a blade in the jaws thereof from position contacting with one facing to position contacting with the other facing and back again, the adjustability of said laterally movable receiver providing for the attainment of equal pressures of the blade against said discs.

2. In a device of the class described, a frame, a shaft revoluble in said frame, pairs of discs axially fixed on said shaft, the discs of each pair being spaced apart and provided with inner abrasive facings, means for rotating said shaft, supports at either side of the disc assembly, a pair of opposed blade holder mountings for each pair of discs, one holder mounting of each pair being pivoted on a support above said shaft and the other on a support beneath said shaft, certain of said blade holder mountings at either side of the disc assembly resting above the shaft and the remainder therebeneath, a blade holder for each holder mounting, each mounting including adjustable receiver elements for altering the angular relation of a holder with respect thereto, two shifter bars, each common to and pivotally connected with the holder mountings at one side of the disc assembly, a tie-bar joining said shifter bars, a crank-wheel geared to said shaft and a pitman

connecting the crank-wheel with said tie-bar, the connection between said pitman and crank-wheel being adjustable radially of the latter.

3. In a device of the class described, a frame, a shaft revoluble therein, a pair of spaced discs, axially fixed on said shaft, each disc being provided with an abrasive facing, means for turning said shaft, a rocker mounting, a blade holder for the mounting, a worm gear on said shaft, a worm wheel in mesh with said gear, a pitman rod having a connection at one end with said worm wheel, and at the other end thereof with said mounting, the connection between said rod and wheel being adjustable radially of said wheel, said rod being adapted to oscillate the mounting and thereby carry a blade in the holder therein from position contacting with one facing to position contacting with the other facing and back again, said mounting embodying means for adjusting the holder with respect thereto, whereby equal pressures of the blade against said discs may be attained.

4. A razor blade sharpener comprising a revoluble shaft, a plurality of stropping disks mounted on said shaft, a plurality of honing disks mounted on said shaft, blade holders positioned at one side of the center of said shaft associated with said stropping disks, blade holders positioned on the other side of said shaft associated with said honing disks, said holders being so arranged that these associated with the honing disks present the blades with their edges opposed to the direction of rotation of the shaft while the holders associated with the stropping disks present the blade edges in the direction of such rotation, means for rotating said shaft, and means for rocking said holders towards and from the faces of said disks.

5. A razor blade sharpener comprising a revoluble shaft, a honing disk mounted thereon, a blade holder adapted to support a blade in proximity thereto with its cutting edge opposed to the direction of rotation of said shaft, a stropping disk mounted on said shaft, a blade holder adapted to support a blade in proximity to said stropping disk with its cutting edge disposed in the direction of rotation of said shaft, and means for moving said blade holders toward and away from said disks.

6. In a device of the class described, a frame, a shaft revoluble in said frame, pairs of discs axially fixed on said shaft, the discs of each pair being spaced apart and provided with inner abrasive facings, means for rotating said shaft, supports at opposite sides of the disc assembly, a pair of opposed blade holder mountings for each pair of discs, one holder mounting of each pair being pivoted on a support above said shaft

and the other on a support beneath said shaft, certain of said blade holder mountings at either side of the disc assembly resting above the shaft and the remainder 5 therebeneath, a blade holder for each holder mounting, and means for swinging said mountings to oscillate the holders and there-

by carry the blades therein back and forth between sharpening positions against their respective abrasive facings.

In testimony whereof, I have signed my name to this specification.

10**HERBERT CLINTON KELLOGG.**
